INVENTOR:

GEORGES MASSIP.

ATTORNEY

J. J. Durie

UNITED STATES PATENT OFFICE.

GEORGES MASSIP, OF PARIS, FRANCE.

AUTOMATICALLY-WORKING STEAM TRAP.

1,406,747.

Specification of Letters Patent. Patented Feb. 14, 1922.

Application filed March 23, 1920. Serial No. 368,154.

To all whom it may concern:

Be it known that I, GEORGES MASSIP, a citizen of the French Republic, and resident of Paris, France, have invented certain new and useful Improvements in Automatically-Working Steam Traps, (for which I have filed application in France Mar. 15, 1919,) of which the following is a specification.

The present invention relates to an automatic steam trap which may be applied to steam pipes, cylinders of steam engines, superheaters, and the like devices and comprising a slidable block provided with peripherical tightening grooves inserted within a suitable chamber or housing, in order to secure an efficient separating of water from the steam and a simultaneous flowing off of the water.

In the accompanying drawing I have shown by way of example two different constructive forms, based on the principle of the invention, of my automatic steam trap:

Fig. 1 illustrates an axial section through a steam trap with a conical block;

Fig. 2 shows a similar section of a steam trap with a cylindrical block.

In Figure 1 the trap is formed by means of a hollow conical housing *a* connected by means of a flange *b* with the device to be purged. A wire gauze or the like *c* is inserted within the connecting duct.

Within the housing *a* is located a block or key *e* provided with a threaded rod *f* operated by a hand wheel or the like *g*. Rod *f* is screwed on the cover *h* of housing *a*, whereby the position of key *d* within the housing may be adjusted.

The end portion *i* of key *e* is provided with apertures *j* establishing a communication between the interior of the housing *a* and the device to be purged. A tube *k* is provided for evacuating the condensed water.

The mixture of steam and water entering the housing *a* through the apertures *j* and flowing towards the evacuating duct *k*, is throttled in the successive grooves *e* forming a labyrinth joint in which the water is separated from the steam, the steam being prevented from escaping. The water accumulates on the bottom of the housing *a* and flows off through the duct *k*.

By operating the hand wheel *g*, key *d* is axially displaced within the housing *a*, whereby not only the entrance and the circulating of the steam into housing *a* but also the degree of saturation of the steam in the

device to which is connected the housing *a*, may be regulated.

In the constructive form shown in Fig. 2, the housing *a* and likewise the key *d*, is of cylindrical shape. The latter, is provided with a threaded operating rod *f* and with hand wheel *g*. Rod *h* ends in a valve needle *m* provided with grooves *n* which put in communication the housing *a* with the boiler or the like, through the small duct *o*. Owing to such arrangement, the position of the key *d*, slideable within the housing *a*, regulates the quantity of entering steam, as it regulates the section of passage *o* through which enters the steam.

The constructive form shown in Fig. 1 is the preferred form, for high pressures, the other constructive form shown in Fig. 2 is preferable for low pressures.

In operation the water of condensation and steam enter through the bore *j* in the projection *i* as shown in Fig. 1 to the chamber containing the body *e* having the grooves. The water adheres to the body in these grooves and tends to prevent the flow of steam past the body and as an excess of water collects it gradually runs off through the outlet *k*. The heat in the water and steam is absorbed by the body which causes it to expand and gives it an axial movement, one end being stationary in the cap *h* causes the whole movement to be imparted to the other end which moves the projection through the bearing opening and closes the bore *j* against the flow of steam. In this way the expansion and contraction of the body will allow the water of condensation to flow out through the casing and at the same time prevent the escape of live steam, the water in the grooves of the body preventing the escape of steam until the body expands sufficiently to close the port *j*.

The same action occurs in the form shown in Fig. 2, the expansion of the body causing the end of the projection to close the duct *o*.

Having now fully described my said invention, what I claim and desire to secure by Letters Patent, is:

1. A steam trap, comprising a cylindrical housing having a bearing opening in one end and a removable cover at the other end, a body formed with annular grooves having a projection at one end seating in the bearing opening, and a threaded projection at the other end having threaded engagement in an opening in the cover, the body having its pe-

riphery spaced from the wall of the housing and formed with a bore in the projection forming an inlet for the passage of fluid and the housing being provided with an outlet at 5 the opposite end.

2. A steam trap, comprising a cylindrical housing having a bearing opening in one end, a cover at the other end and an outlet opening adjacent the cover, a body axially 10 and rotatably mounted in the housing having a projection from one end extending through the bearing opening and provided with a bore for the inlet of fluid, the other

end having a threaded projection threadedly engaging the cover, and the main portion 15 of the body being formed with a plurality of annular grooves, the periphery of the body being spaced from the wall of the housing and in the axial movement thereof adapted to govern the flow of fluid through the trap. 20

In testimony whereof I have hereunto set my hand in presence of two witnesses.

GEORGES MASSIP.

Witnesses:
